UNITED STATES PATENT OFFICE

146,801

DESIGN FOR A COMBINED KEYBOARD AND
TAPE PRINTER FOR ELECTRICAL COM-
PUTING APPARATUSGeorges X. Lens, Antwerp, Belgium, assignor to
International Standard Electric Corporation,
New York, N. Y., a corporation of Delaware

Application September 11, 1944, Serial No. 115,264

Term of patent 14 years

(Cl. D64—11)

To all whom it may concern:

Be it known that I, Georges X. Lens, a citizen of Belgium, residing at Antwerp, Belgium, have invented a new, original, and ornamental Design for a Combined Keyboard and Tape Printer for Electrical Computing Apparatus, of which the following is a specification, reference being had to the accompanying drawings, forming part thereof.

The figure is a perspective view of a combined keyboard and tape printer for electrical computing apparatus, showing my new design, the rear and side not shown being plain.

I claim:

The ornamental design for a combined keyboard and tape printer for electrical computing apparatus, as shown and described.

GEORGES X. LENS.
